CHARLES S. WATT, OF DEDHAM, MASSACHUSETTS, ASSIGNOR TO B. F. STURTEVANT COMPANY, OF BOSTON, MASSACHUSETTS, A CORPORATION OF MASSACHUSETTS.

ELASTIC-FLUID TURBINE.

1,119,481.

Specification of Letters Patent.

Patented Dec. 1, 1914.

Application filed April 17, 1912. Serial No. 691,294.

To all whom it may concern:

Be it known that I, CHARLES S. WATT, a citizen of the United States, residing at Dedham, in the county of Norfolk and State of Massachusetts, have invented certain new and useful Improvements in Elastic-Fluid Turbines; and I do hereby declare the following to be a full, clear, and exact description of the invention, such as will enable others skilled in the art to which it appertains to make and use the same.

The present invention relates to elastic-fluid turbines.

The object of the present invention is to improve the construction of the turbine, and particularly the construction of the parts of the stator exposed to the pressure of the unexpanded fluid, so that the turbine may be more easily assembled, more easily inspected and repaired and more cheaply built.

With the above object in view the present invention consists of the improvements in the construction of elastic-fluid turbines hereinafter described and particularly pointed out in the claims.

In the accompanying drawings which illustrate the preferred embodiment of the present invention; Figure 1 is a longitudinal sectional view of the turbine; Fig. 2 is a perspective view of the exhaust casing showing the rotor in place; and Fig. 3 is a perspective view of the pressure head.

Referring to the drawings, the present invention is illustrated as embodied in a steam turbine of the impulse type in which the steam is expanded in nozzles and is delivered at high velocity to the buckets in which the kinetic energy of the steam is transformed into the mechanical motion of the rotor. The turbine consists of a rotor comprising a bucket wheel 2 having inclined semi-cylindrical buckets 4 milled in its periphery and mounted on the shaft 6, and a stator in which the rotor is mounted and which includes a casing inclosing the bucket wheel. This casing is indicated generally by reference numeral 8 and is hereinafter referred to as the turbine casing. The turbine casing 8 is formed by an exhaust head indicated generally by reference numeral 10 and illustrated in Fig. 2, and a pressure head, or more specifically, a steam head, indicated generally by reference nu-

meral 12 and illustrated in Fig. 3. The steam head or pressure head 12 is so called because it contains the steam chambers or chests through which the high pressure steam from the boiler is led to the turbine buckets. The term exhaust head is applied to the half of the turbine casing which is shown in Fig. 2 to distinguish it from the pressure head, and also because it contains the passage or passages through which the exhaust steam is discharged. The exhaust head 10 and pressure head 12 are bolted together by bolts 14 around their peripheries to form an exhaust chamber 16 surrounding the bucket wheel 2. The exhaust head 10 consists of a cup-shaped casting having a substantially flat circular side wall 18 and a laterally extending annular flange 20 at its periphery. The side wall 18 is somewhat concaved to reduce the size of the chamber 16 near the center of the bucket wheel. The shaft 6 passes through an opening in the side wall 18 which is provided with a stuffing box 22 to form a steam-tight packing for the shaft. At the bottom of the exhaust head 10 pipe-like extensions 24 are provided which discharge the exhaust steam into an exhaust pipe. Usually an exhaust pipe is connected to but one of the pipe-like extensions 24, depending upon the direction of approach of the exhaust pipe, and the other exhaust opening is closed by a closure plate bolted over it. A bracket 26 is cast integrally with the exhaust casing and carries the bearing box 28 which encloses the shaft bearing 30.

The pressure head 12 comprises an annular pressure chest, or more specifically, a steam chest, 40, and a plurality of nozzle-bucket members or segments 42 bolted to the inner face of the pressure chest. The pressure chest 40 is a hollow ring or annulus of a diameter somewhat greater than the bucket wheel 2 and forms an integral part of a substantially flat circular casting 44. The central part of the casting 44 forms a web 46 inside of the annular pressure chest 40 and is concaved, similar to the central part of the other side wall 18, to reduce the size of the exhaust chamber 16 near the center of the bucket wheel. The inner wall of the annular pressure chest 40 and the central web 46 together form one of the side walls of the exhaust chamber 16. The steam

chamber of the pressure chest is cored into the casting 44, so that the pressure chest appears as an annular projection around the outer face of the casting 44. Since the 5 steam chamber is cored into the casting, it has no joints which are subjected to high steam pressure. The shaft 6 passes through an opening through the casting 44 which is closed by a stuffing box 48 to form a 10 steam-tight packing for the shaft. A laterally extending bracket 50 is cast integral with the casting 44 and supports the bearing box 52 which incloses the shaft bearing 54. Two threaded thrust collars 56, one 15 on either side of the bearing 54, provide a longitudinal adjustment for the rotor.

A flanged opening 60 is provided at the bottom of the pressure chest 40 to which a steam pipe 62 is bolted. The steam pipe 62 20 is provided with an emergency valve 64 and a throttle valve 66 which are controlled by governor mechanism 68 mounted on the end of the rotor shaft 6. A number of passages 80 are left through the inner wall of 25 the pressure chest 40 and the steam is discharged through them into the nozzle-bucket segments 42. Each nozzle-bucket segment 42 comprises a flanged base 82 which is bolted to the inner face of the pressure chest 40 by means of bolts 84 and a hollow steam conducting arm 85 which bears at its end an enlarged head 87 in which are formed four return buckets 88 and an expanding nozzle 86. The steam passing 30 through the hollow arms 85 of the nozzle-bucket members is expanded in the nozzles 86 and is delivered at high velocity to the rotor buckets 4 which reverse its direction of flow and direct it into the stationary 35 turn buckets 88, which in turn reverse its direction of flow and redeliver it to the rotor buckets 4. In this connection it is to be noted that the sectional view of the head of the nozzle-bucket member in Fig. 1 of the 40 drawings is taken in a plane considerably inclined to the vertical section of the rest of the turbine so as to better illustrate the inclined nozzle opening 86. After the steam has lost its velocity, it is discharged from 45 the buckets at low pressure into the exhaust chamber 16 from which it is discharged through one of the pipe-like extensions 24 to the exhaust pipe. Valves 90 are provided for closing some of the discharge passages 50 55 so that some of the expanding nozzles 86 may be shut off to increase the efficiency of the turbine on light load. Screw plugs 91 are provided to give access to the inner ends of the nozzle orifices 86 for the purpose of shaping and cleaning them.

The pressure head 12 is, by virtue of its construction, capable of being assembled and tested as an entirety before it is assembled with the rest of the turbine. The pressure head 12 comprises all of the parts of

the stator which are exposed to the boiler pressure of the steam so that it is very desirable to test it for possible leaky joints before it is combined with the rest of the turbine and some of the joints are hidden from inspection and are inaccessible. The 70 pressure or steam head is assembled as follows:—The nozzle-bucket segments 42 are first mounted on templets and their flanges 82 are bored to receive the bolts 84, and then 75 the nozzle-bucket segments are bolted to a templet where their concave faces are machined to fit over the periphery of the bucket wheel 2 with the proper clearance. After the nozzle-bucket segments 42 are 80 prepared, the inner faces of the flanges 82 are ground in place against the face of the steam head casting 44 to form a ground joint 92. They are then bolted to the casting 44, the bolts 84 being received in 85 threaded holes positioned in the casting 44 by means of a templet, so that the ring of nozzle-bucket segments fits, with the proper clearance, over the bucket wheel 2. Since 90 each of the nozzle-bucket segments is separate from all of the other nozzle-bucket segments, in case of repair only the damaged segment need be removed. The steam head is now ready to test for any possible leakage around the ground joints 92 which 95 would be inaccessible after the steam head is assembled with the rest of the turbine. Wooden plugs are tightly driven into the nozzle openings 86, and steam at double the normal working pressure of the turbine is 100 admitted into the pressure chest 40. If the steam head does not show any leaks, it is now ready to be assembled as an entirety with the rest of the turbine. The bucket wheel 2 is placed in the exhaust head 10, as 105 shown in Fig. 2, and then the steam head 12 is bolted to the exhaust head 10 by the bolts 14. The clearance between the periphery of the bucket wheel 2 and the nozzle bucket segments 42 is adjusted by properly positioning the bearing boxes 28 and 52 on the brackets 26 and 50 respectively, where they are securely bolted in place. Longitudinal adjustment of the rotor is had by means of the thrust collars 56 to bring the rotor 110 buckets into longitudinal alignment with the stator buckets. Inspection holes 100 closed by screw plugs 102 are provided through the side of the exhaust head for the insertion of feelers to determine the clearance and 115 alignment between the rotor and stator buckets. It is evident that in case there is any trouble with the high pressure part of the turbine, the pressure head can be removed as an entirety from the rest of the 120 turbine, repaired, tested and replaced.

While the preferred embodiment of the present invention has been specifically illustrated and described, it is to be understood, however, that the present invention may be 125

embodied in other structures within the scope of the invention as defined by the following claims:

1. An elastic fluid turbine having, in combination, a bucket wheel having inclined U-shaped buckets in its periphery, a casing for the wheel including a pressure head comprising a substantially flat circular plate having an annular pressure chamber therein and a plurality of nozzle-bucket segments secured to the inner face of said plate, each nozzle-bucket segment comprising a flanged base bolted to the pressure head, a hollow arm extending from the flanged base, an enlarged head on the end of the arm projecting from the arm toward the periphery of the wheel and extending to one side of the arm along the periphery of the wheel and having inclined U-shaped buckets facing the wheel buckets and an inclined expanding nozzle located in the head on the side next the arm and receiving the fluid through the hollow arm, substantially as described. 75
2. An elastic fluid turbine having, in combination, a bucket wheel having inclined U-shaped buckets in its periphery, a casing for the wheel including a pressure head comprising a substantially flat circular plate at one side of the bucket wheel and spaced from it and a plurality of nozzle-bucket segments secured to the inner face of said plate and arranged in a circle of greater diameter than the wheel, each nozzle-bucket segment consisting of a flanged base bolted to the pressure head, a hollow arm extending from the flanged base laterally toward the bucket wheel across the space intervening between the pressure head and bucket wheel, and an enlarged head on the end of the arm projecting at substantially right angles to the arm toward the periphery of the bucket wheel and along the periphery of the bucket wheel and having inclined U-shaped return buckets facing the wheel buckets and an inclined expanding nozzle located in the head at the place where the head joins its supporting arm and extending from the hollow arm in an inclined direction toward the periphery of the wheel, substantially as described. 90
3. An elastic fluid turbine having, in combination, a bucket wheel having inclined U-shaped buckets in its periphery, a casing for the wheel including a pressure head comprising a substantially flat circular plate having an annular pressure chamber therein and having a flat smooth annular surface on the inside of the plate of greater diameter than the diameter of the bucket wheel and passages through said surface into the pressure chamber, and a plurality of nozzle-bucket segments comprising flanged bases bolted to said annular surface, hollow arms extending from the flanged base toward the 105
4. An elastic fluid turbine having, in combination, a bucket wheel having inclined U-shaped buckets in its periphery, a casing for the wheel including a pressure head comprising a substantially flat circular plate having an annular pressure chamber therein, and having a slightly raised, flat annular surface on the inside of said pressure chamber and passages through said surface into the pressure chamber, and a plurality of nozzle-bucket segments comprising flanged bases bolted to said raised annular surface and having ground joints therewith, hollow arms extending from the flanged base with passages alined with the passages through the annular surface, and heads on the end of the arms having inclined U-shaped return buckets facing the wheel buckets and inclined expanding nozzles receiving the elastic fluid through the hollow arms, substantially as described. 110
5. An elastic fluid turbine having, in combination, a bucket wheel having inclined U-shaped buckets in its periphery, a casing for the wheel including a pressure head comprising a substantially flat circular plate having an annular pressure chamber therein, a concave central portion to reduce the size of the exhaust chamber near the center of the bucket wheel, a flat annular surface on the inside of the plate around the concave central portion and of greater diameter than the diameter of the bucket wheel, and passages through said surface into the pressure chamber, and a plurality of nozzle-bucket segments having flanged bases bolted to said annular surface extending laterally over the bucket wheel and having inclined U-shaped return buckets facing the bucket wheels and inclined expanding nozzles for receiving the elastic fluid through the passages from the pressure chamber and delivering it to the wheel buckets, substantially as described. 115
6. An elastic fluid turbine having, in combination, a bucket wheel having inclined U-shaped buckets in its periphery, a casing for the wheel comprising a pressure head and an exhaust head, said exhaust head being formed of a cup-shaped casting having a substantially flat circular side wall and an annular flange at its periphery extending laterally over and surrounding the periphery of the bucket wheel and having an exhaust passage through said peripheral flange, said pressure head comprising a sub- 120
7. An elastic fluid turbine having, in combination, a bucket wheel having inclined U-shaped buckets in its periphery, a casing for the wheel comprising a pressure head and an exhaust head, said exhaust head being formed of a cup-shaped casting having a substantially flat circular side wall and an annular flange at its periphery extending laterally over and surrounding the periphery of the bucket wheel and having an exhaust passage through said peripheral flange, said pressure head comprising a sub- 125
8. An elastic fluid turbine having, in combination, a bucket wheel having inclined U-shaped buckets in its periphery, a casing for the wheel comprising a pressure head and an exhaust head, said exhaust head being formed of a cup-shaped casting having a substantially flat circular side wall and an annular flange at its periphery extending laterally over and surrounding the periphery of the bucket wheel and having an exhaust passage through said peripheral flange, said pressure head comprising a sub- 130

stantially flat circular plate fitting against the cup-shaped exhaust head, and a plurality of nozzle-bucket segments projecting from the inner face of the pressure head laterally over the periphery of the bucket wheel and having inclined U-shaped return buckets facing the wheel buckets and in-

clined expanding nozzles for delivering the elastic fluid to the wheel buckets, substantially as described.
